BEDRICH ROSENBAUM, OF WALLSEND, ENGLAND.

SHIP'S TORPEDO-TUBE.

1,195,739.

Specification of Letters Patent. Patented Aug. 22, 1916.

Application filed October 28, 1914. Serial No. 868,971.

To all whom it may concern:

Be it known that I, BEDRICH ROSENBAUM, a subject of the Emperor of Austria-Hungary, residing at Wallsend-on-Tyne, England, have invented certain new and useful Improvements in Ships' Torpedo-Tubes, of which the following is a specification.

This invention relates to ships' torpedo tubes which are specially suitable for the 10 broadside launching of torpedoes.

A torpedo launched under water from the side of a ship, while it is in motion, is apt to be diverted out of its correct course by the rolling and pitching of the ship and by 15 the pressure of the water acting laterally on the torpedo as it emerges from the torpedo-tube and, in the case of bow and stern torpedoes, by changing the course of the ship. In order to give freedom of movement to 20 the torpedo during its discharge it has been proposed to gradually enlarge the stern side of the mouth of the torpedo-tube, but, with this arrangement, while freedom is obtained, deflection takes place shortly after the point 25 of the torpedo projects from the side of the vessel with the result that the torpedo is very considerably deflected out of its true course. Further, the side strain on the torpedo, as it is leaving the tube, is apt to 30 break the weak tail part thereof.

Under this invention the torpedo tube is suitably bulged or enlarged at a part thereof in advance of the mouth in such manner, that, when the tail part of the torpedo enters 35 the enlargement, the body of the torpedo will be supported directly or indirectly at, in, or near the mouth of the tube and in such a manner that it can swing or turn on or about this place of support under the 40 action of side pressure thereby lessening the tendency to break the tail part of the torpedo. With this construction of torpedo tube not only is freedom of discharge insured but the amount of deflection from the 45 true course is much reduced.

The shape of the torpedo tube is such that the torpedo is guided straight in the torpedo tube until the side pressure exerted by the water on the emerged portion of the torpedo 50 would, under ordinary conditions, exert a maximum safe strain, any increase of pressure beyond this tending to break or damage the tail of the torpedo, and then, owing to the enlargement, the course of the torpedo is 55 allowed to change (under the side pressure) so that increase of strain on the tail of the

torpedo is avoided. At the moment of change the torpedo can freely deflect from the straight course as it is guided or supported practically at one point only. 60

In order that the invention may be clearly understood I have hereunto appended an explanatory sheet of drawings whereon I have shown, diagrammatically and simply by way of illustration or example, a torpedo 65 and a torpedo tube constructed in accordance with my invention.

Figure 1 shows, in sectional plan, one mode of constructing the torpedo-tube. The torpedo is shown emerging from the tube. 70 Fig. 2 shows part of the torpedo in side elevation and to an enlarged scale. Fig. 3 is a cross section on the line A—A, Fig. 2. Fig. 4 shows another mode of constructing the torpedo-tube. Fig. 5 is a cross section 75 on the line B—B, Fig. 4.

In the construction shown at Fig. 1 it will be seen that the torpedo-tube *a* is made, at the one side thereof (toward the bow) with an enlargement or bulge *b* whose inner surface is preferably formed as a gradual curve or sweep of the shape shown and this enlargement is made sufficiently long to enable the rear end or tail part *c*¹ of the torpedo *c* to enter it as the torpedo itself is deflected 80 by the pressure of the water which acts in the direction indicated by the darts *d*. The part *a* of the tube is straight and is of such length that the torpedo is guided in a straight line until the pressure exerted on 85 the outwardly projecting part of the torpedo becomes sufficiently great to strain the tail part *c*¹ to the maximum permitted or to a predetermined point. When that is reached, owing to the special formation of 90 the enlargement, the torpedo can swing around upon and slide on the part *i* and pass out of the tube without bearing forcibly against the enlargement. In this manner a 95 free discharge is obtained while there is no danger of the tail part of the torpedo being broken.

The torpedo is, preferably, provided with two or more radially arranged guide ribs *j* extending from the cylindrical part of the torpedo to the tail end thereof as shown at Figs. 2 and 3, which ribs, when the torpedo is being discharged, serve as guides and prevent the tail end thereof striking against the mouth or wall of the torpedo-tube as it leaves the same thereby 105 preventing damage. The ribs also serve to stiffen the rear end of the torpedo. *h* indi-

cates the cover of the torpedo-tube which is, of course, shown in the open position.

It will be seen that the torpedo can be projected beyond the ship for about half its length before its end ^{cl} enters the enlargement and, immediately this takes place, the parallel movement of the torpedo ceases and, as it is discharged, it is deflected from its correct course but is soon brought back by the action of the gyroscope.

In the construction shown at Fig. 2, instead of the torpedo-tube having an enlargement at one side, it is provided with a substantially ovate or like enlargement, see also Fig. 5. In this case the torpedo-tube is shown as movably attached (by a ball and socket joint) to the shell of the ship in a suitable and well known manner and as having mounted therein a swivel guide ring
